UNITED STATES PATENT OFFICE.

JOHN CLIFFORD MOORE AND EDWARD L. WINSTON, OF RUSHVILLE, NEBRASKA.

COUPLER FOR PIANOS AND PLAYER-PIANOS.

1,157,573.

Specification of Letters Patent.

Patented Oct. 19, 1915.

Application filed January 14, 1914. Serial No. 812,112.

To all whom it may concern:

Be it known that we, JOHN CLIFFORD MOORE and EDWARD L. WINSTON, both citizens of the United States, and residents of 5 Rushville, in the county of Sheridan and State of Nebraska, have invented a new and Improved Coupler for Pianos and Player-Pianos, of which the following is a full, clear, and exact description.

10 The object of the invention is to provide a new and improved coupler for pianos, player pianos and similar musical instruments arranged to connect any desired sounding device with another, notably, however, to connect a treble sounding device with another treble sounding device one or more octaves higher or lower and connecting a sounding device in the bass with a sounding device an octave higher or lower, so that 15 20 25 30 35 40 45 50 55 60 65 70 75 80 85 90 95 100 105 110 115

when any one sounding device is actuated either by pressing a key or uncovering a hole in the tracker board then the coupled-up sounding device is instantly actuated with the original sounding device.

In order to accomplish the desired result use is made of a valve bar provided with a series of channels each having an air inlet, spring-pressed valves mounted on the said valve bar and controlling the air inlets, the said valves being normally closed and being adapted to be opened by movable members of the piano action such as the abstracts, and a series of pneumatics connected with the piano action and connected with the outlets of said channels. Use is also made of manually-controlled means for moving said valve bar into inactive position relative to its actuating member of the piano action so that the piano can be played by hand without the use of the coupler.

A practical embodiment of the invention is represented in the accompanying drawings forming a part of this specification, in which similar characters of reference indicate corresponding parts in all the views.

Figure 1 is a cross section of a piano provided with the improved coupler; Fig. 2 is an enlarged cross section of part of the same; Fig. 3 is a reduced sectional plan view of the same on the line 3-3 of Fig. 2; Fig. 4 is a sectional perspective view of the valve bar and the valves held thereon; Fig. 5 is a front elevation of part of the piano provided with the improved coupler; Fig. 6 is a transverse section of the same and showing more particularly the manually-con-

trolled means for swinging the valve bar into inactive position; Fig. 7 is a cross section of the valve bar and its connection with the tracker board of a player piano. Fig. 8 is a diagrammatic view showing the flexible tube connections between the pneumatics and the valve bar; and Fig. 9 is a diagrammatic view showing the flexible tube connections between the tracker board, the pneumatics and the valve bar.

The piano shown in Fig. 1 is of the usual construction and is provided with keys A controlling the abstracts B of the usual piano action, having hammers C for sounding the strings D stretched in front of the sounding board E. Each of the abstracts B is provided with an adjustable button F engaged by the free end of the movable member of a pneumatic H of any approved construction, the several pneumatics H being arranged in the piano casing preferably above the keys A, as plainly indicated in Fig. 1. The pneumatics H are connected with the usual wind chest I which in turn is connected by bellows J adapted to be actuated by the feet of the player or by a motor, as the case may be, so that the air is exhausted from the wind chest I.

Sundry of the abstracts are provided with a second adjustable button G located a distance above the button F and each button G is adapted to engage the free end of a valve K controlling an air inlet L' of a channel L formed in a valve bar N extending lengthwise of the piano above the series of pneumatics H, as plainly indicated in the drawings. The outlet end of each channel L in the valve bar N is provided with a nipple L² and each nipple L² that corresponds with a valve K actuated by a button G is connected by a rubber tube O or similar flexible connection with a distant pneumatic H either one, two or more octaves higher or lower than the sounding device used for actuating the valve K.

The valve bar N is connected by a hinge P with a rail Q attached to the piano frame and on which normally rests the valve bar N so that the free rear ends of the valves K extend over the buttons G of the abstracts B. The front ends of the valves K are pivoted at K' on the top of the valve bar N and each valve K is normally held in a closed position on top of the valve bar N by the action of a spring R secured to a spring rail S supported by posts S' from the

valve bar N. The under sides of the valves K are preferably provided with strips K² of felt or other suitable material to tightly close the inlet ends L' of the channels L.

5 The operation is as follows: When the bellows J are actuated and a key A is pressed and the corresponding abstract B is moved upward, then the corresponding hammer C sounds the corresponding string D and at the same time if the raised abstract is provided with a button G, this button lifts the valve K thus allowing air to pass into the channel L and by way of the tube O to a distant pneumatic H to cause the 10 same to collapse. When this takes place the movable member of the collapsing pneumatic H lifts the corresponding button F of the distant abstract B whereby the said distant abstract B is lifted and the corresponding hammer C sounds the corresponding string D, that is, both strings are practically sounded in unison at the same time. As soon as the player releases the key A the first abstract B is lowered and in doing so 15 the button G allows the valve K to close by the action of its spring R so that the distant pneumatic H is free to inflate and in doing so lowers its button F and the abstract B connected therewith. From the foregoing 20 it will be seen that by the arrangement described a second sounding device is automatically actuated as soon as the sounding device with which it is coupled is actuated so that both sounding devices are actuated 25 simultaneously. The second sounding device may be one, two or more octaves higher or lower than the first sounding device by correspondingly connecting the pipes O with the corresponding pneumatics H and 30 the channels L.

In practice the connections are preferably made as shown in Fig. 8, in which sundry of the bass pneumatics, preferably twelve in number, are coupled with second sounding 35 devices an octave lower. The abstracts B of the coupled primary sounding devices control the corresponding valves K of the valve bar, and the corresponding nipples L² of the valve bar are connected by rubber tubes O with the said second sounding devices. Sundry of the treble pneumatics, preferably 40 twenty-two in number, are connected in a similar manner with second sounding devices two octaves higher.

45 The sounding devices of the middle section of the key board are not coupled up as these sounding devices are frequently used when playing chords and require no coupling up. The last four sounding devices in 50 the bass are also not coupled up as they are seldom used.

In connecting for hand playing it is only necessary to make the connections as shown in Fig. 8, so as to operate thirty-four second sounding devices, twelve in the bass by first

or straight octaves and twenty-two in the treble by second octaves. Therefore only thirty-four of the abstracts are provided with the button G for moving the valve K, corresponding to the second sounding devices. 75

By the arrangement shown, not more than twelve notes are connected in the bass by straight octaves and not more than twenty-two in the treble by second octaves and 75 therefore the sounding of third sounding devices is prevented. It is understood that in hand playing the upper nipples L² in the valve bar are not used and are plugged.

When it is desired to throw the coupler 80 out of action it is only necessary to swing the valve bar N upward into the position shown in dotted lines in Fig. 6, so that the free ends of the valves K are out of the path of the buttons G. In order to impart a 85 swinging motion to the valve bar N use is made of a link Q' pivotally connected with the valve bar N and extending to the front of the piano so as to be within convenient reach of the player, as will be readily understood by reference to Fig. 6.

When it is desired to use the coupler on a player piano then use is made of supplementary channels L³ each connected with an adjacent corresponding channel L, and 95 the outlet of each auxiliary channel L³ is provided with a nipple L⁴ connected by a rubber tube T with a tracker board opening U' of a tracker board U over which passes the note sheet V for uncovering the tracker 100 board openings U' in the usual manner. It will be noticed that when a tracker board opening U' is uncovered by the note sheet V then air is admitted to the channels L³ and L so that the pneumatic H, in the player 105 chest I connected by the pipe O with the said channel L is deflated to actuate the corresponding abstract B.

In practice the connections are preferably made as shown in Fig. 9 in which sundry of the bass pneumatics, preferably twelve in 110 number, are connected by tubes O leading from the nipples L² of the valve bar to connect with second sounding devices an octave lower. Sundry of the treble pneumatics, 115 preferably twenty-two in number, are connected with second sounding devices two octaves higher, by the tubes O, which connect the nipples L² of the valve bar with said second sounding devices.

The last four sounding devices in the bass and the sounding devices of the middle section of the keyboard are shown as connected directly with the player chest and with the corresponding tracker board openings U' by 125 tubes T'. It will be seen that there is no actuation of a third sounding device as before explained in reference to the arrangement disclosed in Fig. 8.

As shown in Fig. 9 the pneumatics of the 130

primary sounding devices, that are coupled with second sounding devices, are connected directly with the corresponding tracker board openings U' by tubes T' so that the said primary sounding devices are actuated, as before described, when the corresponding tracker board openings are uncovered by the note sheet. The sounding devices in the bass and treble that are not coupled up are 13 also connected directly with the corresponding tracker board openings by tubes T' .

Tubes T connect tracker board openings U' with the nipples L^4 of the valve bar corresponding to the nipples L^2 to which the 15 tubes O are connected so that air can pass directly from the tracker board openings through the channels of the valve bar to the pneumatics corresponding with said tracker board openings. By tracing the connections 20 from the tracker board openings through the valve bar and across to the nipples on the player chest, it will be seen that the arrangement does not interfere with the correct note sheet reading of the tracker board 25 when the valve bar is out of gear, and when the valve bar is in gear certain of the tracker openings are coupled up with second sounding devices.

It is understood that by having two 30 rows L^2 and L^4 the desired connections can be readily made with the pneumatics H and the tracker board U to actuate a corresponding sounding device, and that a distant sounding device can be actuated in conjunction 35 with one actuated by uncovering a tracker board opening by the note sheet. It is also understood that nipples L^2 or L^4 not used for making a connection are closed up by plugs L^5 , as shown in Fig. 2.

40 In the arrangement shown in Fig. 8, for hand playing only, the piano can be played with the valve bar either in or out of gear, and in the arrangement as shown in Fig. 9, with the tracker board connections, the 45 player piano can be played through the tracker board connections with the valve bar either in or out of gear, or it can be played by hand either with or without the valve bar in gear by leaving the note sheet on the 50 tracker board at a point where there are no perforations in the note sheet.

In Figs. 8 and 9, J' indicates the tube leading from the player chest I to the bellows. In these figures only the valves K for 55 thirty-four second sounding devices, and the corresponding nipples or openings in the valve bar N are indicated.

Having thus described our invention, we claim as new and desire to secure by Letters 60 Patent:

1. In a musical instrument of the character described having sets of bass and treble pneumatics, the combination of a piano action, a valve bar extending lengthwise of 65 the instrument above the pneumatics and having air inlet channels, spring-pressed valves mounted on top of the said valve bar and each controlling the inlet of an air inlet channel, the said valves being normally closed, means connecting the said valves 70 with movable members of the piano action to open the said valves, the sets of bass and treble pneumatics being connected with sundry of the bass and treble sounding devices of the piano action, and means connecting 75 the said bass and treble pneumatics with the outlets of corresponding air inlet channels, the valves of which are controlled by sounding devices of higher or lower octaves, the said valve bar being adapted to be moved 80 out of operative position to prevent the sounding of an octave when a primary sounding device is actuated.

2. In a musical instrument of the character described having sets of bass and treble 85 pneumatics, the combination of a piano action, a valve bar extending lengthwise of the instrument above the pneumatics and having a series of air inlet channels, spring-pressed valves mounted on top of the said valve bar 90 and each controlling the inlet of an air inlet channel, the said valves being normally closed, means connecting the said valves with movable members of the piano action to open the said valves, the sets of bass and 95 treble pneumatics, being connected respectively with sundry of the bass and treble sounding devices of the piano action, means connecting the said bass pneumatics with the outlets of the said air channels, the valves of which are controlled by sounding devices an 100 octave higher, and means connecting the said treble pneumatics with the outlets of the said air channels, the valves of which are controlled by sounding devices two octaves lower, and means for moving the valve 105 bar out of operative position to permit of ordinary playing.

3. In a musical instrument of the character described, the combination of a piano 110 action having bass and treble sounding devices adjustable buttons on sundry of said abstracts of the piano action, a valve bar provided with air inlet channels, spring-pressed valves mounted on the said valve 115 bar and each controlling the inlet of an air inlet channel, the said valves being normally closed and each being adapted to be opened by one of the said buttons on a corresponding abstract, sets of bass and treble 120 pneumatics connected with sundry of the said bass and treble sounding devices, a second adjustable button on each abstract of the piano action each pneumatic engaging a second button on the corresponding abstract, means connecting the said bass and 125 treble pneumatics with the outlets of corresponding air inlet channels, the valves of which are controlled by sounding devices of higher or lower octaves, and means for mov- 130

ing at will the valve bar out of operative position relative to the valve operating buttons, to permit of ordinary hand playing.

4. In a musical instrument of the character described, the combination of a piano action having bass and treble sounding devices adjustable buttons on sundry of the abstracts of the piano action, a valve bar provided with air inlet channels, spring-pressed valves mounted on the said valve bar and each controlling the inlet of an air inlet channel, the said valves being normally closed and each being adapted to be opened by one of the said buttons on a corresponding abstract, sets of bass and treble pneumatics connected with sundry of the said bass and treble sounding devices, a second adjustable button on each abstract of the piano action each pneumatic engaging a second button on the corresponding abstract, flexible tubes connecting the said bass and treble pneumatics with the outlets of corresponding air inlet channels, the valves of which are controlled by sounding devices of higher and lower octaves, a fixed rail on which the said valve bar is hinged, and manually controlled means for swinging the said valve bar into inactive position to disconnect the valves from the said first buttons to permit of hand playing in the ordinary manner.

5. In a musical instrument of the character described, the combination of a piano action having bass and treble sounding devices adjustable buttons on sundry of the abstracts of the piano action, a valve bar provided with air inlet channels, spring-pressed valves mounted on the said valve bar and each controlling the inlet of an air inlet channel, the said valves being normally closed and being each adapted to be opened by one of the said buttons on a corresponding abstract, a second adjustable button on each of the abstracts of the piano action sets of bass and treble pneumatics, of which the bass set of pneumatics is connected with the second abstract buttons of sundry of the said bass sounding devices, and the treble set of pneumatics is connected with the second abstract buttons of sundry of the treble sounding devices, flexible tubes connecting the said bass pneumatics with the outlets of the said air inlet channels, the valves of which are controlled by sounding devices an octave higher, and flexible tubes connecting the said treble pneumatics with the outlets of the said air inlet channels, the valves of which are controlled by sounding devices two octaves lower, the said valve bar being movable at will into inactive position to disconnect the sounding devices of said octaves from the primary sounding devices.

6. In a musical instrument of the character described, the combination of a piano

action having bass and treble sounding devices, a button on each abstract of the piano action and engaging the corresponding pneumatic, a coupling bar provided with channels having air inlets and outlets, valves mounted on said bar and each controlling the inlet of an air channel, a second button on sundry of the abstracts of the piano action, each of said second buttons controlling a corresponding valve of said coupling bar to open the same and admit air to an air inlet channel when the corresponding sounding device is actuated, tubes connecting the outlets of the said air channels with a corresponding number of pneumatics having sounding devices of higher or lower octaves than the sounding devices that actuate the said valves, thereby actuating second sounding devices; when the sounding devices controlling the valves are actuated, the abstracts of the second sounding devices being provided only with the first mentioned buttons, whereby the sounding of third sounding devices is prevented, and means whereby the coupling bar may be moved into inactive position to prevent the sounding of second sounding devices when the first sounding devices are actuated.

7. In a musical instrument of the character described, the combination of a piano action having bass and treble sounding devices, and bass and treble pneumatics connected with the said sounding devices, a valve bar extending lengthwise of the instrument above the pneumatics, the said valve bar having air inlet channels, pivoted and spring pressed valves mounted on the said valve bar and projecting at their rear ends beyond the bar, the said valves each controlling the inlet of an air inlet channel and being normally closed, buttons on the abstracts of the piano action and each engaged by the corresponding pneumatic, sundry of the said abstracts being each provided with a second button located above the first button, the said second buttons corresponding in number with the said valves and adapted to engage the projecting ends of the valves to open the same, and flexible tubes connecting sundry of the bass and treble pneumatics with the outlets of said air inlet channels, the valves of which are controlled by sounding devices of higher or lower octaves, the said valve bar being hinged and adapted to be swung into inactive position to move the free ends of the valves out of the path of the said second buttons.

8. In a musical instrument of the character described, the combination of a piano action having bass and treble sounding devices and bass and treble pneumatics connected with the sounding devices, of a coupling bar hinged to the frame of the instrument and adapted to be moved into and out of operative position, the said coupling bar

having channels provided with air inlets and outlets, means whereby primary sounding devices may be actuated whether the coupling bar is in or out of operative position, and means connecting the outlets of the air channels of the coupling bar with pneumatics of second sounding devices to operate said second sounding devices in unison with the primary sounding devices when the coupling bar is in operative position.

9. In a musical instrument of the character described, the combination with a wind chest, bass and treble pneumatics, connected with the wind chest, a piano action having bass and treble sounding devices, and abstracts for controlling the corresponding sounding devices, each abstract having a button engaging the movable member of a pneumatic and adapted to be lifted thereby when the pneumatic is collapsed, of a coupling bar hinged to the frame of the instrument and adapted to be moved into and out of operative position, the said coupling bar being provided with channels having air inlets and outlets, the coupling bar extending lengthwise of the instrument above the series of pneumatics, valves mounted on said bar and each controlling the inlet of an air channel, springs for normally holding the

valves closed, a second button on sundry of 30 the abstracts of the piano action above the first button, each of said second buttons controlling a corresponding valve of said coupling bar when the latter is in operative position, to lift the valve to admit air to an 35 air channel when the corresponding sounding device is actuated, and flexible tubes connecting said outlets of the air channels with channels of the wind chest corresponding to pneumatics having sounding devices 40 of higher or lower octaves than the sounding devices by which the said valves are actuated, the abstracts of the second sounding devices being provided only with the first mentioned buttons, whereby when the said 45 pneumatics are collapsed and the abstracts corresponding thereto are lifted to sound the said second sounding devices, the sounding of third sounding devices is prevented.

In testimony whereof we have signed our 50 names to this specification in the presence of two subscribing witnesses.
